UNITED STATES PATENT OFFICE.

LOUIS WILPUTTE, OF NEW ROCHELLE, NEW YORK, ASSIGNOR OF TWO-THIRDS TO
ALICE A. WILPUTTE, OF NEW ROCHELLE, NEW YORK.

COKE-CHAMBER AND DISCHARGING-GUIDE THEREFOR.

1,360,608.

Specification of Letters Patent. Patented Nov. 30, 1920.

Application filed May 4, 1918. Serial No. 232,467.

To all whom it may concern:

Be it known that I, LOUIS WILPUTTE, a subject of the King of Great Britain, and a resident of New Rochelle, county of Westchester, in the State of New York, have invented certain new and useful Improvements in Coke-Chambers and Discharging-Guides Therefor, for which the following is a true and exact description, reference being had to the accompanying drawings, which form a part thereof.

My present invention relates to horizontal coke ovens of the type in general use in which the opposite ends of each coking chamber are normally closed by doors which are removed at the time of discharging from the chamber a coke charge previously formed therein. In this type of oven, after the doors are removed, the previously formed coke mass is discharged by means of a "ram" or pusher which is forced into the coking chamber at the "pusher side" of the battery and pushes the coke mass out through the other end of the coking chamber, at the "coke side" of the battery. Normally the coke is discharged on to a quencher car which in practice cannot be brought into close proximity to the adjacent ends of the coking chambers. To guide the coke mass in its passage from the coking chamber to the quencher car, a traveling coke guide is ordinarily employed. The general object of the present invention is to provide a coke oven structure and traveling coke guide of the general type referred to with coacting features which improve and simplify the construction and reduce the time and care required to bring the coke guide into co-operative relation with a coking chamber to be discharged.

The various features of novelty which characterize my invention are pointed out with particularity in the claims annexed to, and forming a part of this specification. For a better understanding of the invention, however, and its advantages, reference should be had to the accompanying drawings and descriptive matter in which I have illustrated and described a preferred embodiment of my invention.

Of the drawings:

Figure 1 is an elevation of my improved coke guide and oven structure with parts of the latter broken away and in section.

Fig. 2 is a plan view of the coke guide and a portion of the oven structure; and

Fig. 3 is a partial section on the line 3—3 of Fig. 2.

In the drawings, A represents the masonry body of a horizontal coke oven battery of a type well-known and in general use.

In this type of oven the masonry forming the oven structure proper is supported at the opposite sides of the battery by a metallic frame-work. This frame-work at the coke side of the battery comprises in the construction illustrated, vertical buckstays B, and flashplate sections C. E, represents the coke wharf or platform at the "coke side" of the battery. The wharf or platform E is shown as lying some distance below the floor level of the coking chambers A' and is provided with track rails, E' and E² extending parallel to the length of the battery, that is, transverse to the lengths of the horizontal coking chambers A'. The coke guide F employed consists essentially in the form shown of a truck having a pair of wheels F' and a pair of wheels F² running on the rails E' and E² respectively; and a chute mounted on the truck. The chute has sides formed by metallic boards or slats F² and a bottom F³ formed of heavy metallic plates. The floor F³ of the coke guide is adapted to register edge to edge with metallic bodies D, secured to the metallic frame-work at the coke side of the battery and forming extensions of the floors of the coking chambers A'. As shown, each member D is in the form of a cast metal plate which is secured at its ends to the buckstays B, located at the opposite sides of the coking chamber A' to which the member D pertains. As shown, each member D is bolted at each end to the horizontal flange of a bracket B', riveted to a corresponding buckstay. At its inner edge each member D abuts against the corresponding transverse bottom flash plate section C' which forms a part of the floor of the oven chamber proper.

To prevent the inner side of the coke guide from lifting under the thrust impressed upon it by the coke mass being discharged I provide the coke guide and the metallic frame-work of the oven structure with interlocking parts. These are formed

in the preferred construction illustrated by means of an angle bar G, secured to the coke guide and having its horizontal flange projecting inward from the inner end of the chute floor F³, and lying beneath and in close proximity to the underside of the oven floor extension member D of an oven chamber A' in front of which the coke guide is placed. As shown, each member is formed adjacent its outer edge with a depending rib or flange D', which adds stiffness to the member, and may also serve to prevent the guide from moving inward toward the oven structure far enough to permit the coke guide floor F³ to strike the end of an adjacent member D as the coke guide is moved along the track rails E' and E². As shown the vertical flange of the angle bar G is secured to a heavy channel bar F⁵ forming a part of the truck frame of the coke guide. Advantageously, the outer edge of each oven floor extension member is undercut and the adjacent edge of the coke guide floor F³ is similarly beveled, so as to reduce the tendency of coke fragments to wedge in the open joint between these edges. F⁶ represents a link by which the coke guide carriage may be connected to the door machine H, or other motor driven device also running on the coke wharf rails E' and E².

With the described construction, the labor and care necessary to bring the coke guide into proper position in front of the discharge end of a coking chamber A' to be "pushed" is obviously reduced to a practical minimum. The interlocking provisions between the metallic framework of the battery and the coke-oven guide effectively prevent any tendency of the inner edge of the coke guide to lift under the very considerable thrust which may be impressed upon it by the coke mass being ejected from the oven chamber through the coke guide.

While in accordance with the provisions of the statutes I have illustrated and described the best form of my invention now known to me, it will be apparent to those skilled in the art that changes may be made in the form of the apparatus disclosed without departing from the spirit of my invention as set forth in the appended claims, and that some features of my invention may sometimes be used to advantage without a corresponding use of other features of the invention.

Having now described my invention, what I claim as new and desire to secure by Letters Patent, is:-

1. In the coke oven battery having horizontal coking chambers and having a metallic frame-work and a coke guide track at the

coke side of the battery, the combination of metallic parts secured to said frame-work and forming extensions of the coking chamber floors and a coke guide movable along said track and comprising a floor adapted to register, edge to edge with the metallic floor extension of an oven chamber in front of which the coke guide is placed and co-operating parts carried by said coke guide and said frame-work which interlock to prevent the inner edge of the coke guide from lifting under the thrust of the coke mass being pushed. 65

2. In a coke oven battery having horizontal coking chambers and having a metallic frame-work comprising vertical buckstays at the coke side of the battery and also having a coke guide track at the coke side of the battery, the combinations of metallic members secured to the buckstays and forming extensions of the coking chamber floors projecting outwardly beyond the outer edges of the buckstays, and a coke guide mounted on said track and comprising a floor adapted to register, edge to edge with the metallic floor extension member of each oven chamber in front of which the coke guide is placed. 70

3. In a coke oven battery having horizontal coking chambers and having a metallic frame-work and a coke guide track at the coke side of the battery, the combination of metallic parts secured to said frame-work and forming extensions of the coking chamber floors and a coke guide movable along said track and comprising a floor adapted to register, edge to edge with the metallic floor extension part of an oven chamber in front of which the coke guide is placed, the outer edge of each of said metallic parts being undercut and the adjacent edge of the coke guide floor being correspondingly beveled. 90

4. In a coke oven battery having horizontal coking chambers and having a metallic frame-work, comprising vertical buckstays at the coke side of the battery and also having a coke guide track at the coke side of the battery, the combination of metallic members secured to the buckstays and forming extensions of the coking chamber floors projecting outwardly beyond the outer chamber in front of which the coke guide is mounted on said track and comprising a floor adapted to register, edge to edge with the metallic floor extension of each oven chamber in front of which the coke guide is placed, said coke guide being formed with a shoulder which passes under the outer portion of said metallic members. 100

LOUIS WILPUTTE.
